CHRISTIAN F. BACHLER, OF PHILADELPHIA, PENNSYLVANIA.

DESIGN FOR A RADIATOR.

SPECIFICATION forming part of Design No. 23,631, dated September 4, 1894.

Application filed June 12, 1894. Serial No. 514,341. Term of patent 3½ years.

To all whom it may concern:

Be it known that I, CHRISTIAN F. BACHLER, a citizen of the United States, residing at Philadelphia, in the county of Philadelphia and 5 State of Pennsylvania, have invented and produced a new and original Design for Flue Radiators; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 Figure 1 is a side view of the end loop of the flue radiator. Fig. 2 is a side view of an intermediate loop of the flue radiator. Fig. 3 shows a vertical section of one intermediate loop and half of the second, and the front view of one 20 half of an intermediate loop, and one of the whole end loops of the flue radiator. Fig. 4 shows a horizontal section of one intermediate loop, and one half of the second, and the top view of one half of an intermediate loop, and 25 of the whole end loop of the flue radiator.

a represents the end panel showing a heron standing on one leg, the other one raised, in the midst of various water plants, looking upward and eyeing a butterfly balancing on the end of a sheave of the reeds.

30

b, b are the dolphin shaped feet of the end loop.

c, c is a band of semicircular scales with a narrow fillet running over the center of the same, and small spherical knobs in the corners of the fillet and the scales.

35

e, e is a scrolled separator between the ribs d, d and the lugs f, f.

What I claim is—

The design for a flue radiator herein shown 40 and described.

In testimony whereof I affix my signature in presence of two witnesses.

C. F. BACHLER.
